CLAIM

The ornamental design for a spent catalyst container, as shown and described.

DESCRIPTION

FIG. 1 is a perspective view of a spent catalyst container showing our new design;

FIG. 2 is a front elevation view thereof, the rear elevation view being a mirror image of that shown;

FIG. 3 is a right side elevation view thereof, the left side being a mirror image of that shown;

FIG. 4 is a top plan view thereof; and

FIG. 5 is a bottom plan view thereof.

The fragmentary criss-cross pattern shown on the top of the container in FIGS. 1 and 4 is understood to be continuous throughout the area shown.

*Fig. 1.**Fig. 2.**Fig. 3.**Fig. 4.**Fig. 5.*
